FINGER RING

George A. Flynn, Warwick, R.I., assignor to Drexel
Institute of Technology, Philadelphia, Pa., a cor-
poration of Pennsylvania

Filed Nov. 28, 1966, Ser. No. 4,832

Term of patent 14 years

(Cl. D45—10)

Fig. 1

Fig. 2

Fig. 3

Fig. 4

FIGURE 1 is a top plan view of a finger ring embodying my new design;

FIGURE 2 is a bottom view thereof;

FIGURE 3 is a right side elevational view thereof; and
FIGURE 4 is a left side elevational view thereof.

The dominant features of the design reside in the full line portions of the drawings. It is understood that those portions shown in dotted lines could be altered in shape and size within the scope of the invention.

I claim:

The ornamental design for a finger ring, substantially as shown and described.
